UNITED STATES PATENT OFFICE.

ERNEST R. VIBERG, OF MONTREAL, QUEBEC, CANADA.

COMBINED END-STAKE POCKETS AND END-SILL BRACE.

1,137,812.

Specification of Letters Patent.

Patented May 4, 1915.

Application filed April 10, 1914. Serial No. 830,937.

To all whom it may concern:

Be it known that I, ERNEST R. VIBERG, a subject of the King of Great Britain, and resident of the city of Montreal, in the 5 Province of Quebec and Dominion of Canada, have invented new and useful Improvements in Combined End-Stake Pockets and End-Sill Braces, of which the following is a full, clear, and exact description.

10 This invention relates to improvements in combined end stake pockets and end sill braces, sometimes known as coupler horn braces, and the object is to provide means for bracing the end sill of a car at the point 15 over the coupler.

A further object is to provide end stake pockets located inside the end sill.

Still another object is to provide a device 20 complying with the requirements of railway commissions, regarding the location of end stakes.

The device consists essentially of a casting located between and secured to the channels of the center sill, and secured also to 25 the end sill. This casting is provided with pockets for the reception of the end stakes.

In the drawings which illustrate the invention: Figure 1 is a half plan view of the device. Fig. 2 is a vertical section on the 30 line 2—2, Fig. 1. Fig. 3 is an end elevation, the end sill being removed.

Referring more particularly to the drawings, 5 designates the channels and 6 the cover plate forming the center sill. The 35 end sill 7 may be connected to the center sill in any suitable way, and is provided with a wooden buffer 8 immediately above the draft gear 9. The brace consists of a vertical plate 10 secured to the end sill having 40 a pair of pockets 11 attached thereto inside the end sill. At each side of the brace a horizontal flange 12 is provided between the front plate 10 and the outside of the pocket, said flanges overlying the top of the center 45 sill channels and being secured thereto. A top plate 13 extends from the front plate 10 rearwardly, and passes under the cover plate 6 to which it is attached. This top plate occupies the space between the pockets, and 50 as will be clearly seen its upper surface is in line with the lower surface of the flanges 12. The outer side of each pocket is continued rearwardly beyond the rear wall 14 of the pocket to form a web 15, supporting the rear 55 portion of the top plate and attached to the

center sill channels. The device is completed by a bottom plate 16 which extends rearwardly from the front plate between the center sill channels. This plate connects the lower ends of the pockets and also the 60 lower edges of the webs 15. An opening 17 is provided in the bottom of each pocket for the escape of cinders, water and the like. The outer wall of each pocket is provided on its inner surface with a plurality of vertically disposed ribs 18, which strengthen the wall and reduce the area of contact between the pocket and stake. In order to facilitate the insertion and removal of end stakes, the rear wall 14 of each pocket is 70 slightly inclined, as shown in the drawings. It will be seen that the front plate 10 and pockets 11 project considerably above the top plate 13, so as to allow for floor thickness. 75

From the foregoing description, and drawings, it will be seen that the device which is preferably a casting has very great strength, the various walls being so disposed as to support and stiffen one another. This 80 casting forms a very strong brace between the center and end sills immediately over the draft gear and to the rear of the buffer 8. The end sill is thus stiffened at the point where it receives greatest shock in coupling 85 cars and the like. In addition, pockets are provided inside the end sill as required by railway commissions. This requirement has for its object the provision of additional space between the cars for the protection of 90 train men. Where the end stakes are outside the end sill, it is possible for the cars to come so closely together that a train man would be crushed between the end stakes of the two cars. With the stakes placed inside 95 the end sills, this becomes impossible under ordinary circumstances.

Having thus described my invention, what I claim is:—

1. The combination with the center and 100 end sills of a car, of a brace connected between said sills having end stake pockets formed therein.

2. The combination with the center and 105 end sills of a car, of a brace connected between said sills having open bottomed end stake pockets formed therein.

3. The combination with the center and 110 end sills of a car of a brace inserted in and secured to said center sill and to the end sill

above the draft gear, and open bottomed end stake pockets formed in said brace having ribbed side walls.

4. In a car, the combination with center 5 and end sills, of end stake pockets located in the center sill inside the end sill.

5. In a car, the combination with center 10 and end sills, of end stake pockets located in the center sill inside the end sill, said pockets being rigidly connected to the center and end sills above the draft gear and forming an end sill brace.

6. The combination with a center sill built 15 up of spaced channels and a cover plate and with an end sill, of an end sill brace mounted between the channels of the center sill and secured to the channel webs and flanges and to the cover plate, and secured to the end sill, and end stake pockets formed in 20 said brace.

7. The combination with a center sill built 25 up of spaced channels and a cover plate and with an end sill, of a hollow member comprising front, top, bottom and side walls, the front wall thereof being attached to the end 30 sill, the side walls to the center sill channels, and the top to the center sill cover plate, and flanges extending between said front and top walls over the flanges of the center sill channels and attached thereto.

8. The combination with a center sill built 35 up of spaced channels and a cover plate and with an end sill, of a hollow member comprising front, top, bottom and side walls, the front wall thereof being attached to the end sill, the side walls to the center sill channels, and the top to the center sill cover plate, and pockets formed in said member between the side sill channels extending 40 from the bottom wall of the member above the top wall.

9. The combination with a center sill built

up of spaced channels and a cover plate and with an end sill, of a hollow member comprising front, top, bottom and side walls, 45 the front wall thereof being attached to the end sill, the side walls to the center sill channels, and the top to the center sill cover plate, and pockets formed in said member between the side sill channels extending 50 from the bottom wall of the member above the top wall.

10. The combination with a center sill comprising spaced channels and a cover plate and with an end sill, of a brace secured 55 between the center and end sills above the draft gear, comprising a front wall attached to the end sill and extending between the center sill channels above same and laterally to the edges of the channel flanges, vertical 60 side walls extending rearwardly from said front wall attached to the inner surfaces of the center sill channels; a top wall connecting said side walls and front wall and attached at its rear edge under the cover plate, 65 and an apertured bottom wall connecting the side and front walls, pockets formed in said member having inner side walls parallel with the member side walls and projecting above the top wall, and inclined rear 70 pocket walls extending between the pocket side walls and member side walls, the apertures of the bottom wall being bounded by said pocket walls, ribs on the member side walls projecting into said pockets, and 75 flanges extending between the front wall and side walls above the center sill channels and attached thereto.

In witness whereof, I have hereunto set my hand in the presence of two witnesses. 80

ERNEST R. VIBERG.
